US0D1095775S

(12) **United States Design Patent** (10) **Patent No.:** **US D1,095,775 S**
(45) **Date of Patent:** **** Sep. 30, 2025**

(54) **ADAPTER**

(71) Applicant: **SHENZHEN WISDOM SCIENCE AND TECHNOLOGY CO., LTD,**
Shenzhen (CN)

(72) Inventor: **Hui Sun**, Shenzhen (CN)

(73) Assignee: **SHENZHEN WISDOM SCIENCE AND TECHNOLOGY CO., LTD,**
Shenzhen (CN)

(**) Term: **15 Years**

(21) Appl. No.: **29/868,779**

(22) Filed: **Dec. 14, 2022**

(51) **LOC (15) Cl.** **23-01**

(52) **U.S. Cl.**

USPC **D23/262**

Primary Examiner — George J Ulsh

Assistant Examiner — Kathryn Elizabeth Zieno

(57) **CLAIM**

The ornamental design for an adapter as shown and described.

DESCRIPTION

FIG. 1 is a perspective view of a first embodiment of an adapter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of the adapter;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the drawings depict portions of the adapter that form no part of the claimed design.

1 Claim, 8 Drawing Sheets
